UNITED STATES PATENT OFFICE.

EBEN S. CHATFIELD, OF HYDE PARK, PENNSYLVANIA.

EXPANSIBLE WHEEL.

SPECIFICATION forming part of Letters Patent No. 269,916, dated January 2, 1883.

Application filed November 11, 1882. (No model.)

To all whom it may concern:

Be it known that I, EBEN S. CHATFIELD, of Hyde Park, in the county of Lackawanna and State of Pennsylvania, have invented certain new and useful Improvements in Expansible Wheels; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My improvements relate to a special construction of sprocket or chain wheels, whereby they are not only expansible, but also better adapted for heavy chains, and for lifting and conveying material by means of the chains, and for firmly holding the adjustable radial arms or sections of the wheel in their adjusted positions to resist the weight and strain of the chain and of the bodies which may be lifted or conveyed by it.

Figure 1 is a face view, and Fig. 2 a view of the opposite face, of my improved wheel; Fig. 3, its center plate detached; Fig. 4, a perspective of one of the radial arms; Fig. 5, a central section of two of the wheels on a common shaft, the shaft being broken partly away; and Fig. 6, a piece of chain with blocks attached.

The main body of the wheel is composed of a plate, A, having a central hub, and of a series of radial peculiarly-constructed sprocket-pieces B, hereinafter more fully described. The perimeter of the plate A, instead of being circular, is polygonal, having as many angles, c, as there are radial arms or sprocket-pieces, and it is beveled or rounded off at one side of its perimeter, as shown at d, to adapt it to the corresponding underside of the flanges e of the pieces B. That side or face f of the wheel to which these pieces B are attached has a series of tapering or V-shaped projections or lugs, g, cast integral with the plate, and extending a short distance from the outer edge of the plate toward the center of the wheel, and slots h are cut through the body of the plate to admit of adjustably attaching to it the shanks of the pieces B by means of adjusting screws or bolts i.

The pieces B are made as follows: Their outer ends are severally made with a deep longitudinal groove, j, and two shallower recesses

or grooves, k k', and in these grooves k k', about midway of their lengths, are projecting nibs or pins l l', adapted to take hold of and carry those links of a linked chain which would lie flat, while the intervening links, which lie edgewise when on the pieces B, drop into the deeper grooves j. That flange e of each of the pieces B which is adjacent to the outer edge of plate A is curved on its underside, as shown, to conform to the part d of the plate, so that when the two are brought close together they may bear upon each other, thus supporting the flange.

Suitable bolts or screws, i, which may be provided with washers n and nuts, if desired, are passed through the slots h, and serve to hold the several sprocket-pieces B against the plate, and set-screws o, which enter threaded holes in the inner ends of these pieces, abut against the central hub, p, of plate A, and serve the double purpose of meeting the thrust and strain on the sprocket-pieces when the chain is on and performing its duty, and also of adjusting these pieces outward or inward from the center when it is desired to enlarge or diminish the size of the wheel to tighten or slacken the chain, so as to adjust the wheel to the chain to cause the nibs to strike the links at the proper time and place to overcome the stretching due to wear, &c.

For heavy work or for lifting, ordinary expansible pulleys are impracticable, because the belts must slip, nor for such work will it do to have the periphery of the wheel in true arcs of a common circle, for the same reason. I therefore make the outer ends of the pieces B straight, as shown, instead of curved, and they are thus also adapted each to receive a link of the chain substantially in the manner of ordinary non-expansible or solid sprockets.

The screws o should have square or polygonal heads, so as to be readily turned and set by a wrench. Instead of these screws, wedges or cams may be employed, or other appropriate device which can be interposed between the hub and the inner ends of the radial sprocket-pieces to sustain the thrust.

It will be evident that minor variations in the form and construction may be made without departing from the spirit and principle of my invention. For instance, the nibs l may be longer or shorter or differently located on the

end of the pieces B; or there may be more or less of them, to adapt them to the character of the chain employed. Any number of pieces B may be employed, the plate in such case being 5 adapted for the desired number.

My wheel is adapted or adaptable for belts as well as for chains. I have found it very successful as a conveyer for bark in a tannery, and for such and kindred purposes of conveying or lifting I attach to the outer side of the chain or belt bars or other devices, as shown 10 as *q* in Fig. 6.

I claim—

1. The expansible sprocket-wheel described, 15 composed of the plate A, its hub *p*, slots *h*, and

lugs *g*, in combination with the radially-adjustable sprocket-pieces B, bolts *i*, and set-screws *o*, or equivalents, bearing against the hub.

2. In a polygonal sprocket-wheel, the deep groove *j*, extending all around its periphery, 20 and the shallower short grooves or recesses *k* at each side of groove *j*, and with the intercepting nibs *l l'*, serving to strike the links at the right time to overcome the stretching due to wear, &c.

EBEN S. CHATFIELD.
